UNITED STATES PATENT OFFICE.

FLOYD C. WEAVER, OF WASHINGTON, DISTRICT OF COLUMBIA.

GRINDING MACHINE.

Application filed May 2, 1922. Serial No. 557,939.

To all whom it may concern:

Be it known that I, FLOYD C. WEAVER, a citizen of the United States, residing at Washington, District of Columbia, have invented certain new and useful Improvements in Grinding Machines, of which the following is a specification, reference being had therein to the accompanying drawings.

The object of this invention is to provide 10 a driving mechanism for moving a lapping plate relative to a work carrying plate in a desired orbit and for varying the orbit and the position of the orbit in respect to the work carrying plate so that the grinding 15 may be performed in a desired manner.

With these and other objects in view, my 20 invention comprises certain novel combinations, constructions and arrangements of parts as will be hereinafter described, illustrated in the accompanying drawings, and more particularly pointed out in the appended claims.

In the drawings:

Figure 1 is a plan view of the lapping 25 machine showing the relative arrangement of the lapping plate and the work carrying plate and the driving mechanism operating the lapping plate, etc., and the controlling equipment.

Figure 2 is a vertical section on the line 30 2-2, in Fig. 1, taken in the direction indicated by the arrows, and shows the general arrangement of the lapping plate and the work carrying plate relative to the operating 35 and driving mechanism.

Figure 3 is a vertical section on the line 35 3-3, in Fig. 1, taken in the direction of the arrows, and shows the relative position of the lapping plate and its operating pin relative to the work carrying plate and its 40 driving mechanism.

Figure 4 is a vertical section on the line 40 4-4, in Fig. 1 taken in the direction of the arrows showing the relative position of the 45 driving eccentrics for the operating mechanism for the lapping plate, and the driving mechanism.

Figure 5 is a vertical section on the line 50 5-5, in Fig. 1 taken in the direction of the arrows, and shows the relative arrangement 55 of the main driving shaft and power pulley etc., and parts of the operating and control mechanisms.

Referring to Figure 1, the lapping plate 55 2 is moved by the pin 3 over the work carrying plate 1. The pin 3 is securely clamped

in the end of arm 31, which also carries at the opposite end from pin 3 a forked hinge bearing on the bearing collar 30 of the driving pin 29. Thus the pin 3 is securely connected to driving pin 29. The stroke arm 31 carries the adjustable clamping blocks 32 secured by screws 33, and forming the socket bearing for the ball end of bar 23 thus forming a flexible joint. Bar 23 is secured in 60 sliding adjustment in stroke arm 22 by the clamping screws 34. The stroke arm 22 carries at its opposite end a fork hinge joint to the bearing collar 21 on the driving pin 20. Thus the pin 3 is free to be lifted vertically from its socket in lapping plate 2, also 65 the pin 3 is actuated by the combination of the motions of the driving pins 29 and 20. Driving pin 29 is securely but adjustably clamped in the slot 35 of the oscillating arm 70 36 which is securely attached to the vertical oscillating axis 28. This axis 28 is in turn carried upon the two arms 37 and 38 which 75 also form bearings for the oscillation of axis 28. Arm 26 is also firmly secured to 80 axis 28, and at its opposite end carries the hinge pin 25 capable of being securely set in adjustment in the slot 27. The arm and strap 17 of the main driving eccentric 18 is connected to arm 26 by the pin 25. Thus the 85 driving pin 29 is actuated through pin 25 of driving eccentric strap 17 of the main driving eccentric 18. The driving pin 20 is secured in adjustment in the slot 24 of the eccentric plate 19. Thus driving pin 20 is 90 actuated by the eccentric plate 19. Hence 95 the movement of the pin 3 is a combination of the strokes of the two driving eccentrics 18 and 19.

Referring to Figure 2 in conjunction with Figure 1, axis 28 is carried in working bearings of arms 37 and 38, each being securely fastened to the vertical axis 42. Arm 38 is formed so that its outer end forms the sector of a worm wheel meshing with the worm pinion 39 secured on the shaft 40. Thus with arms 37 and 38 each securely fastened to the oscillating axis 42, the axis 28 can then be swung about the axis 42 by the driving shaft 40 through the medium of the worm pinion 39. The shaft 40 is provided with a hand wheel 41 at its outer end, thus enabling the operator at will to swing the axis 28 about the axis 42.

Referring to Figures 4 and 5 in connection with Figure 1, the eccentric driving plate 19 and the driving eccentric 18 are 110

each securely fastened to the vertical spindle 43, so that by turning the spindle 43 the eccentric plate 19 and the driving eccentric 18 may be set to position the seat 24 and eccentric at a desired angle with respect to the shaft 40. Attached to the vertical spindle 43 is the driving worm or gear wheel 45 engaging the worm or gear pinion 16 securely fastened to the main driving shaft 14.

10 This main driving shaft 14 carries the power driving pulley 13 which may be connected to or disconnected from the main driving shaft 14 by the clutch 11 operated by lever 12. The bevel gear 15 is securely fastened to 16 main driving shaft 14 and engages the bevel gear 9 secured firmly to the separate length of shaft 8. This short length of shaft 8 carrying gear 9, is connected at will of operator by the clutch 6, operated by lever 7, 20 to the main portion of shaft 8 which carries the firmly secured worm or pinion gear 5 and the hand wheel 10 at its outer end.

Referring to Figure 3 in connection with Figure 1, the work carrying plate is securely 25 fastened to the vertical spindle 46. The driving worm wheel or gear 4 is firmly secured to this vertical spindle 46, and meshes with the worm or gear pinion 5 on shaft 8. Thus by moving the clutch 6 to an inoperative 30 position, the work carrying plate 1 is then free to be rotated by hand wheel 10, even while lapping plate 2 is being driven over the work carrying plate 1 by the pin 3.

Also by operating hand wheel 41, the axis 35 28 is swung about the axis 42, while the machine is in operation, thereby causing the orbit of the pin 3 to be shifted over the surface of the work carrying plate 1. By this shifting of the orbit of pin 3 in conjunction with the rotation of the work carrying plate 1 by hand wheel 10, the lapping effect of the plate 2 can be distributed at the will of the operator over any desired portion 40 of the plate 1. Also when desired, plate 1 can be left to rotate automatically and the position of the path of strokes of plate 2 varied as desired by hand wheel 41.

While I have described the preferred embodiment of my invention, and have illustrated the same in the accompanying drawings, certain minor changes or alterations may appear to one skilled in the art to which this invention relates, during the extensive manufacture of the same and I, therefore, 55 reserve the right to make such alterations or changes as shall fairly fall within the scope of the appended claims.

Having described the present invention what is claimed as new is:

60 1. In a grinding and lapping machine of the character described, the combination of a work carrying plate, means for supporting said work carrying plate, a lapping plate positioned above said work carrying plate, a pin connected to said lapping plate, a

stroke arm connected to said pin, means connected to the stroke arm intermediate its ends for oscillating said stroke arm, and means connected to said stroke arm at the end thereof for shifting the same forwardly and rearwardly, thereby shifting said lapping plate in a variable manner, as and for the purposes set forth. 70

2. In a grinding and lapping machine of the character described, the combination of a work carrying plate, means for supporting said work carrying plate, a lapping plate positioned above said work carrying plate, a pin connected to said lapping plate, a stroke arm connected to said pin, a bar connected to said stroke arm intermediate its ends, means adjustably connected to said bar for driving the same with an adjustable stroke, whereby said bar will oscillate said stroke arm with an adjustable stroke, and driving means adjustably connected to the rear end of said stroke arm for advancing and retracting said stroke arm with an adjustable stroke, whereby said lapping plate will be moved in a variable manner, as and for the purposes set forth. 80

3. In a grinding and lapping machine of the character described, the combination of a work carrying plate, means for supporting said work carrying plate, a lapping plate positioned above said work carrying plate, a pin connected to said lapping plate, a stroke arm connected to said pin, a bar connected to said stroke arm, an eccentric drive plate, means for driving said plate, a connecting means engaging said eccentric plate, a second stroke arm of a tube like construction receiving said bar and said connecting means, means adjustably connecting said bar and said connecting means to said second stroke arm, and driving means connected to the rear end of said first stroke arm, as and for the purposes set forth. 100

4. In a grinding and lapping machine of the character described, the combination of a work carrying plate, means for supporting said work carrying plate, a lapping plate positioned above said work carrying plate, a pin connected to said lapping plate, a stroke arm connected to said pin, a vertical oscillating axis, means for supporting said axis, an oscillating arm connected to said axis and to the rear end of said stroke arm, an arm connected at one end to said axis and having a slot in its opposite end portion, a main driving eccentric, means for driving said eccentric, a strap surrounding said eccentric and having a substantially triangular strap arm extending therefrom and carrying a pin at its apex, said pin fitting in said slot, as and for the purposes set forth. 110

5. In a grinding and lapping machine of the character described, the combination of a work carrying plate, means for supporting

said work carrying plate, a lapping plate positioned above said work carrying plate, a pin connected to said lapping plate, a stroke arm connected to said pin, a fixed vertical axis, upper and lower arms pivotally mounted upon said fixed axis, a vertical oscillating axis carried by the outer ends of said upper and lower arms, whereby said last mentioned axis is movably supported, the outer end of the lower arm being formed to provide a sector shaped worm gear, a

shaft having a worm pinion thereon engaging said worm gear, an oscillating arm connected to the upper end of said second-mentioned axis and to said stroke arm, a fourth arm connected to said second axis, and means for driving said last-mentioned arm, as and for the purposes set forth. 15

In testimony whereof I hereunto affix my signature.

FLOYD C. WEAVER.
